Primary Examiner — Khawaja Anwar*Assistant Examiner* — Julice Seung Eun Oum(57) **CLAIM**

The ornamental design for a running machine, as shown and described.

DESCRIPTION

FIG. 1 is a front, top and right perspective view of a running machine showing my new design;

FIG. 2 is a front view thereof;

FIG. 3 is a rear view thereof;

FIG. 4 is a left side view thereof;

FIG. 5 is a right side view thereof;

FIG. 6 is rear, top and right perspective view thereof with a handrail and a controller;

FIG. 7 is a partially enlarged view of the area "7" in FIG. 1; and,

FIG. 8 is a partially enlarged view of the area "8" in FIG. 1. The bottom view is omitted since the bottom view is invisible in normal use.

The broken lines depict portions of the running machine is embodied that form no part of the claimed design.

The broken lines showing of the handrail and the controller for the purpose of illustrating the environmental structure and forms no part of the claimed design.
